UNITED STATES PATENT OFFICE.

WILLIAM L. CLAUSE, OF PITTSBURGH, PENNSYLVANIA, ASSIGNOR TO PITTSBURGH
PLATE GLASS COMPANY, A CORPORATION OF PENNSYLVANIA.

METHOD OF CASTING PLATE-GLASS.

1,298,893.

Specification of Letters Patent. Patented Apr. 1, 1919.

Application filed January 12, 1912. Serial No. 670,746.

To all whom it may concern:

Be it known that I, WILLIAM L. CLAUSE, a citizen of the United States, residing at Pittsburgh, in the county of Allegheny and State of Pennsylvania, have invented certain new and useful Improvements in Methods of Casting Plate-Glass, of which the following is a specification.

The invention relates to casting plate glass, and it has for its primary objects: the provision of an improved method of getting the glass out of the tank and properly placing it on the casting table previous to the rolling operation. These, together with such other objects as may hereinafter appear or are incidental to my invention I attain by means of a construction illustrated in preferred form in the accompanying drawings, wherein:—

Figure 1 is a diagrammatic plan view of the glass tank, casting table and leer, together with my improved means for securing a distribution of the glass metal on the casting table; and Fig. 2 is a side elevation 25 of Fig. 1, partly in section.

In carrying out my method, I employ a construction of glass tank which comprises two compartments, 7 and 8, suitably connected by a passage or connection 9. The compartment 7 is the melting furnace proper, and the compartment 8 is a refining compartment into which the glass metal flows from the melting compartment. The compartment 7 is maintained at a temperature of approximately 2550° Fhr., and the refining compartment at approximately 2000° Fhr., which has been found to be the temperature best suited for the casting operation. The refining compartment 8 is provided with a discharge spout 10, which may be either a gravity or a non-gravity spout, adjacent which is located the casting table 11, having the usual roller 12 for rolling the glass into sheets. The spout is closed 40 by the gate 13, and both spout and gate are maintained by the jets 17 at approximately the same temperature as that of the refining compartment.

It will be noted that the casting table 11 and roller 12 are positioned at an angle of 90° to the tank and spout, instead of being

parallel thereto. The glass is drawn onto the table by means of a U-shaped hoe-like implement 14 which is inserted into the tank 8 through the gate and immersed or partially immersed in the glass. On being withdrawn from the tank, it carries along the glass segregated between its rearwardly projecting wings 15 and during the continued movement of the hoe across the table 11, the glass metal thus withdrawn is properly deposited and spread on the table, the continuation of the movement carrying the chilled glass adjacent the hoe clear past the table where it falls as waste and is thus prevented from becoming incorporated in the manufactured sheet or plate. The glass is then rolled by the roller 12 in the usual manner and the plate of glass formed is moved into the leer 16 where it is annealed in the usual manner. The hoe 14 is of a size to segregate a large quantity of glass, sufficient, if desired, to form an entire sheet or plate, and in order to properly manipulate it, I have provided a hoist 18 supported from a crane 19 traveling on the tracks 20, the shaft 21 of the hoist being adjusted vertically by means of a rack and pinion, or other suitable mechanism. This arrangement permits of any movement longitudinally, laterally and vertically as may be found necessary to secure proper distribution of the glass on the casting table. The hoe is loosely supported at the end of the shaft 21 in such manner that it may be tilted to secure its immersion in the tank.

By maintaining the spout and gate at the same temperature as the refining chamber, the glass is brought to the table in a condition best suitable for rolling. Other advantages will appear to those familiar with the art.

Having thus described my invention and illustrated its use, what I claim as new and desire to secure by Letters Patent is the following:—

The herein described process of casting plate glass from a tank having an outlet spout adjacent the surface of the glass, which consists in engaging a body of glass in the tank at a point remote from the outlet spout with a raking tool, and drawing

such body of glass to the outlet spout and therethrough upon a casting table, and then spreading and rolling the glass, heat being applied to the said spout to prevent chilling of the glass before its application to the casting table.

In testimony whereof I have hereunto

signed my name in the presence of the two
subscribed witnesses.

W. L. CLAUSE.
